DESIGN FOR A HANDLE FOR BRUSHES

Erich Gronemeyer, Pompton Plains, N. J., assignor to Mack Molding Company, Incorporated, Wayne, N. J., a corporation of New Jersey

Application February 1, 1945, Serial No. 117,701

Term of patent 14 years

(Cl. D9—2)

To all whom it may concern:

Be it known that I, Erich Gronemeyer, a citizen of the United States of America, residing at Hopper Avenue, Pompton Plains, Morris County, State of New Jersey, have invented a new, original, and ornamental Design for a Handle for Brushes, of which the following is a specification, reference being had to the accompanying drawing forming part thereof.

The figure is a perspective view of a handle for brushes embodying my new design. The ornamentation extends completely around the handle in precisely the relation illustrated on the side shown.

I claim:

The ornamental design for a handle for brushes, as shown and described.

ERICH GRONEMEYER.
